TO THE BABCOCK PRINTING PRESS MANUFACTURING COMPANY, A CORPORATION
OF CONNECTICUT.

GRIPPER-TENSIONING MECHANISM FOR PRESSES.

Original application filed May 6, 1925, Serial No. 28,355. Divided and this application filed September 2, 1926. Serial No. 133,214.

The present case is a division of our co-pending application Ser. No. 28,355, filed May 6, 1925.

The present invention relates to mechanism for holding the grippers upon the sheet and the same is adapted for use in printing presses as well as cutting and creasing presses. In present practice it is customary to provide a shaft which is carried by the impression cylinder of the press and on the shaft are mounted a series of curved fingers, commonly called grippers, which impinge against the forward edge of the sheet which is to be printed or cut and creased, pressing the edge of the sheet against the forward or leading edge of the impression portion of the cylinder. Generally the grippers are closed on the sheet by spring action, and they are opened by means of a cam through a lever action which turns the gripper shaft. When the grippers first act on the sheet the latter is stationary and the inertia of the sheet must be overcome practically instantly. This places a heavy burden upon the grippers when the sheet is first started, and requires much greater holding force than is afterwards necessary to carry the sheet around with the impression cylinder. If there is any slippage between the sheet and grippers while the sheet is starting from the dead stop position, this will affect the register of the printing. The object of the present invention is to provide means for placing an additional pressure or tension upon the grippers while the inertia of the sheet is being overcome, and this pressure may be continued during any portion of the revolution of the cylinder, although in practice it has been found necessary to apply this additional pressure only during the starting of the sheet and for a very short period thereafter. If the ordinary springs usually employed for closing the grippers upon the sheet are made sufficiently stiff to provide the extra pressure required during the starting of the sheet, there is difficulty in opening the grippers to deliver or take the sheet and the gripper operating mechanism in such case is subject to rapid wear. In the present case we have shown means separate from the ordinary means for pressing the grippers, which places an additional or auxiliary pressure upon them at the moment they are closed upon the

sheet. Another object of our invention is to accomplish the above mentioned results with the fewest number of parts operating in a simple manner.

In the drawings forming part of this application,

Figure 1 is a sectional view of an impression cylinder of a press to which our invention has been applied,

Figure 2 is a plan view of the same, and

Figure 3 is an enlarged sectional view of the principal part of the invention.

In the drawings we have shown the impression cylinder 1 such as is employed in a two-revolution printing press, and it is to be understood that this may represent the impression cylinder of a cutting and creasing press. The sheet engages around the impression surface of the cylinder while it is being printed or cut and creased in cooperation with the flat form or circular form on the bed or type cylinder, these latter parts not being represented in the drawings. At 2 we have shown the end of the feed table which is arranged adjacent the surface of the impression cylinder 1 and from which the sheets are fed over the forward edge of this board into position to be taken by the grippers on the impression cylinder. It may be here stated that the mechanism here described may be used in connection with any other cylinder on which the sheet travels and the principle of operation will be the same. At 4 we have shown the shaft which extends longitudinally of the cylinder and it is mounted on a suitable bracket 4^a of the cylinder and it is known as the gripper shaft and it carries a number of grippers 5 of which only one is shown in the drawing. These grippers are secured to the shaft in such position that the tips of the grippers will impinge the sheet against the leading edge of the impression portion of the cylinder. The ordinary device for operating these grippers to grip and release the sheet comprises a crank arm and cam, as shown in our said copending application.

On the shaft 4 there is fixed a notched disc 34 and there is a pawl 35 pivoted upon the stud 36 so that the free end of the pawl engages the shoulder 48 of the notched disc 34. The pawl has a pivotal motion upon the stud 36 and the latter is secured to a lever 37

which is fixed to the shaft 38 mounted in the cylinder to oscillate in the bearings 39 and 40. Outside of the cylinder there is a lever arm 54 secured to the shaft 38 and it carries a 5 roller 40^a which is adapted to be acted upon by a cam 41 stationarily fixed to a portion 42 of the press frame. This roller 40^a is held pressed against the cam by means of a spring 43 which surrounds the rod 44. One end of 10 the spring presses against the lever 37 while the other presses against a spring step 46 attached to the cylinder at 47. The pawl 35 is forced against the shoulder 48 by means of a compression spring 49 which surrounds the 15 rod 50 and is compressed between the spring step 51 which is part of the lever 37, and against the under side of the pawl 35. There are nuts 52 and 53 at opposite ends of the rod 50 and by adjusting these nuts the pawl 35 20 may be regulated in position to engage the shoulder 48.

In the drawings we have shown this device in the position in which the pawl is engaged with the shoulder 48 of the disc 34 at which 25 time the spring 49 is exerting pressure upon the pawl 35 and through the disc 34 causing a rotating pressure upon the shaft 4 to apply auxiliary force to the grippers 5 to hold them pressed against the edge of the sheet at the 30 time the latter is being taken and until the inertia of the sheet has been overcome. Considering the cylinder 1 turned back from the position shown in the drawings until the roller 40^a is engaged with the high portion 35 of the cam 41, at this time the grippers 5 will be slightly open to allow the forward edge of the sheet to be fed to the forward edge of the impression portion of the cylinder. At this time the lever 37 will be rocked slightly anti-clockwise in Figure 1 so that the point of the pawl 35 will be disengaged from the shoulder 48 of the disc 34 and it will be slightly below the shoulder 48. As the cylinder proceeds to move to the left from the position above 45 described, the roller 40^a will finally run into the lower portion of the cam 41 and the point of the pawl 35 will move slightly clockwise and also upwardly in relation to the disc 34 so that it will come into contact with the 50 shoulder 48 just before or at the instant the grippers are pressed against the sheet by the ordinary gripper closing mechanism, which latter will be the same as in said copending application. Any slight irregularity of adjustment of the parts may be compensated for 55 through the spring 49. In case the cylinder is turned backwardly the spring 49 will allow the grippers to be opened without injury.

As the cylinder continues to revolve anti-clockwise in Figure 1 and after the roller 40^a has moved to the lowest point on the cam 41 the roller 40^a will be gradually lifted by reason of the fact that the cam 41 has slightly increasing radius following its lowest point; 60 and this causes the pawl 35 to be released so

that additional auxiliary pressure on the shaft 4 is released at or before the time approaches for the opening of the grippers. In a two-revolution press the cylinder is in raised position at the time the grippers take 70 the sheet and it is lowered at the time the grippers are opened to deliver the sheet, and this raising and lowering motion of the cylinder in relation to the fixed cam 41 in itself is sufficient to throw the auxiliary mechanism 75 out of action at the time the grippers are opened, if desired.

It is obvious that the still or inactive period of the cam can be of any convenient length so that the additional pressure on the grippers 80 may be applied merely for a brief time when the sheet is taken and then immediately released, or the additional pressure may be maintained during a considerable portion of the printing cycle of the press. The main requirement is that the additional pressure is to be exerted at the time the sheet is first 85 taken by the grippers and until the inertia of the sheet has been overcome.

Having described our invention, what we 90 claim is:

1. In a press the combination of a cylinder adapted to carry a sheet, grippers thereon for engaging and holding the sheet to move with the cylinder, said grippers being mounted on a shaft having means adapted to be engaged by a latch, a latch arranged to operate thereon to press the grippers upon the sheet, and means for automatically causing said latch to act on said grippers to press the sheet 95 while in the initial gripping position and for automatically releasing said latch before the opening of said grippers. 100

2. In a press the combination of a cylinder adapted to carry a sheet, grippers thereon for engaging and holding the sheet to move with said cylinder, said grippers being mounted on a shaft having means adapted to be engaged by a latch, a latch arranged to operate thereon to press the grippers upon the sheet, and means for automatically causing said latch to act on said grippers to press the sheet 110 while in the initial gripping position and for automatically releasing said latch before the opening of said grippers, embodying a cam 115 for releasing said latch.

3. In a press the combination of a cylinder adapted to carry a sheet, grippers thereon for engaging and holding the sheet to move with said cylinder and adapted to be actuated by the ordinary closing means, said grippers being mounted on a shaft, means operating independently of the ordinary gripper actuating means for pressing the grippers on the sheet and including means on said shaft 120 adapted to be engaged by a latch, a latch arranged to operate thereon to press the grippers upon the sheet, and a stationary cam for releasing said latch. 125

4. In a press the combination of a cylinder 130

- adapted to carry a sheet, grippers thereon for holding and moving the sheet and adapted to be actuated by the ordinary closing means and means for operating independently of the ordinary actuating means for pressing the grippers on the sheet, said grippers being mounted on a shaft having means adapted to be engaged by a latch, a latch carried by said cylinder and spring means for operating the same to press the grippers, and means for causing said latch to engage said means on said shaft when the sheet is taken by the grippers and for releasing the latch prior to the opening of the grippers.
5. In a press the combination of a cylinder adapted to carrying a sheet, grippers there-
- on for engaging the sheet and moving it with the cylinder, said grippers being mounted on a shaft having means adapted to be engaged by a latch, a lever attached to said cylinder and having an arm, a cam for operating on said lever arm to rock said lever, a spring for holding said lever arm engaged with said cam, a latch carried by said lever for engaging the means on said shaft, and 20 spring acting on said latch to exert a closing pressure on the grippers.
10. 5. In a press the combination of a cylinder adapted to carrying a sheet, grippers there-
- on for engaging the sheet and moving it with the cylinder, said grippers being mounted on a shaft having means adapted to be engaged by a latch, a lever attached to said cylinder and having an arm, a cam for operating on said lever arm to rock said lever, a spring for holding said lever arm engaged with said cam, a latch carried by said lever for engaging the means on said shaft, and 25 spring acting on said latch to exert a closing pressure on the grippers.
15. Signed at the city and county of New London, State of Connecticut, this 18th day of August, 1926.
